UNITED STATES PATENT OFFICE.

JAMES L. HAYES, OF MARIETTA, NORTH CAROLINA.

LAMP-EXTINGUISHER.

1,159,219.

Specification of Letters Patent.

Patented Nov. 2, 1915.

Application filed April 19, 1915. Serial No. 22,502.

To all whom it may concern:

Be it known that I, JAMES L. HAYES, a citizen of the United States, residing at Marietta, in the county of Robeson and 5 State of North Carolina, have invented certain new and useful Improvements in Lamp-Extinguishers; and I do hereby declare the following to be a full, clear, and exact description of the invention, such as will enable others skilled in the art to which it 10 pertains to make and use the same.

This invention relates to lamp extinguishers, the object of the same being to provide a simple device to be operated by a lever underneath the burner for instantly extinguishing the flame of the lamp wick.

Another object of the invention is to provide a device which will prevent the flame from smoking the chimney of the lamp, and 20 one that will be especially convenient on lanterns and signal lights which must be inclosed in a casing.

Another object of the invention is to simplify the construction of extinguishers, and 25 to render them more efficient in use.

The foregoing and other objects may be attained by means of the construction illustrated in the accompanying drawing, in which—

30 Figure 1 is a side elevation of a lamp burner having an extinguisher connected thereto and made in accordance with this invention, said burner being shown with the cap thrown up to expose the wick tube and 35 extinguisher, Fig. 2 is a top plan view of the same, Fig. 3 is a perspective view of the extinguisher removed from the burner, and Fig. 4 is a detail perspective view of one of the shutter supports for the extinguisher.

40 Referring to the drawing, the numeral 1 designates an ordinary kerosene lamp burner provided with a hinged cap, a wick tube 3, and a series of chimney springs 4 of the usual construction. It will be understood 45 however that the lamp extinguisher may be connected to any suitable burner.

U-shaped supporting devices 5 and 6 are provided with angular feet 7 and 8, each provided with a rivet hole 9, and rivets 50 tend through these holes for connecting the supports to the burner at opposite ends of

the wick tube 3. The supports 5 and 6 are each provided with integral pintles 10 struck up from the body of the supports, said pintles 10 extending through the shutters 11. The shutters 11 are each provided with inclined side portions 12 connected by plain upper edges 13 which when closed over the wick tube 3 will extinguish the flame. 60

The shutter members 11 are each provided with integral projections 14, and connected to said projections is a ring 15 having a shank 16 connected to a finger lever 17. The finger lever is indicated by the numeral 18 65 as an entirety. Connected to the finger lever 18 is a spring 19 having a coiled portion 20 and its terminal carrying upon the upper side of the foot 21 of one of the chimney springs 4. The lever 18 is pivoted at 22 to 70 a bracket 23 depending from the underside of the burner, and said lever is provided with a finger piece 24.

When it is desired to extinguish the lamp, the finger piece 24 is lifted up, which throws 75 down the inner end of the lever and closes the shutters together with their two edges 13 in contact.

The invention is simple in construction, is reliable in operation and can be manufactured at comparatively low cost. 80

Various changes may be made in the details of construction without departing from the spirit and scope of the invention as defined in the claims. 85

What is claimed is:—

1. A lamp extinguisher comprising U-shaped supports having integral pintles formed therein, shutters pivoted to said pintles and provided with projecting portions, a ring connected to said projecting portions, and a lever connected to the shank of said ring, said lever being pivoted to a bracket on the burner, and a spring connected to the lever and adapted to hold it to its uppermost position. 95

2. A lamp extinguisher comprising U-shaped supports each having a pair of integral pintles struck therefrom and bent at right angles thereto, said supports being 100 connected to the lamp burner at opposite ends of the wick tube, extinguisher shutters

pivoted to said pintles and provided with extended end portions, a ring surrounding said projecting portions, a shank connected to said ring; a lever connected to said shank, said lever being pivoted to a bracket under the burner and provided with a finger piece, and a spring connected to said lever and having a coiled portion and a terminal seat-

ed under the burner on one of the chimney springs.

In testimony whereof I affix my signature in presence of two witnesses.

JAMES L. HAYES.
